ROTARY SWITCH CONTACT ASSEMBLY

Walter L. Dietrich, Hartford, Conn., assignor to
The Arrow-Hart & Hegeman Electric Company,
Hartford, Conn., a corporation of Connecticut

Application May 27, 1946, Serial No. 672,394

14 Claims. (Cl. 200—155)

1

This invention relates to rotary electric switches and more particularly to switches wherein the switch blades and stationary contacts are required to carry and to break high amperage electric currents.

It is an object of the invention to provide rotary blades or plates with adequate cross-sectional area to carry several hundred amperes and also with flexibility for the purpose of providing adequate pressure, yet permitting contact separation without the exercise of excessive rotary force.

Another object of the invention is to provide improved means associated with the rotary switch blades and the stationary contacts for minimizing cooling and snuffing out the arc incident to contact separation.

Another object is to provide an arc snuffing element which will also function as a guide and thus to keep at a minimum the required number of switch parts.

Other objects and advantages of the invention will appear as the invention is described in the accompanying drawings.

In the drawings—

Fig. 1 is a plan view partly broken away of a switch blade assembly embodying the invention;

Fig. 2 is a transverse section view taken along line 2—2 of Fig. 1;

Fig. 3 is a section view taken along line 3—3 of Fig. 2; and

Fig. 4 is a detailed perspective view of one of the stationary contacts.

Referring to the drawings, the invention is shown as made for embodiment in a rotary electric switch having two stationary contacts which are bridged by a two blade rotary bridging contact. It will become obvious to those skilled in the art, as the invention is described, that the invention is equally applicable to switches having a greater number of fixed contacts and blades.

The fixed contact members 10 and 12 comprise flat blocks or bars of copper or other highly conductive material. These fixed contacts are alike and therefore only one will be described in detail. The inner or contacting ends are enlarged in arcuate form to provide a contact head 13, whose top and bottom surfaces 13a and 13b are flat and in the plane of the main body of the contact. The inner portion of the contact head is cut away from both the top and bottom surfaces to provide inner contact surfaces 14a and 14b a step below and above the surfaces 13a and 13b. Preferably the end portions of the inner step 14 of the contact head are convergently inclined as at

2

14c and beveled. The stationary contacts are or may be spaced 90° apart around the axis of a rotary switch blade assembly.

The rotary switch blade assembly is built up of a number of elements. Top and bottom switch plates 22 and 24 lie against the top and bottom surfaces respectively, of circular discs 26 and 28 made of insulating material. For convenience in description the plates 22 and 24 will be termed primary bridging members. Between the discs 26 and 28 are switch plates 34 and 36 which are spaced from the discs by conductive washers 32 and 33. For convenient reference the plates 34 and 36 will be termed secondary bridging members. They are spaced apart by three conductive washers 38 to provide room for a middle insulating disc 40 between the secondary bridging members 34 and 36. All of the switch plates, washers and both discs 26 and 28 are preferably provided with a square central aperture for the reception of a switch operating shaft (not shown) by means of which the rotary switch blade assembly may be turned. The plates, washers and discs 26 and 28 are firmly secured together as by rivets; but the middle disc is free within the assembly, being retained between the plates 34 and 36 so that the assembly may rotate while the middle disc remains stationary as will hereinafter be more fully described.

Referring now in detail to the several elements which make up the rotary switch blade assembly, the primary bridging members 22 and 24 are illustrated as plates stamped in L-shape from sheet metal. Since they are identical in form, only one need be described. The bridging plate member 22 has a central portion 23 from which arms 25, 27 extend radially. The arms are slotted to provide parallel blades 25a and 25b and 27a and 27b. By reason of the slotting of the radially extending arms the alignment of the movable contacts with the fixed contacts and a maximum number of points of contact between the switch plates and fixed contacts are provided. Preferably the side edges at the ends of the blades are outwardly flared, as for example, at 25f to facilitate contact engagement and disengagement and to bring about a quicker complete engagement of the individual blade of the movable contact arms as the movable switch member is moved into contacting position and also to prolong, for the maximum period, the complete engagement of the individual arms when the movable contact is moved for contact separation.

In order to provide an adequate amount of contact surface in engagement between the fixed

and movable contact member so as to prevent overheating and without increasing the width of the individual contact members, the secondary bridging members 34, 36 are provided. Since these members are alike only one will be described. They are stamped from sheet metal as L-shaped plates. The member 34 comprises a central portion 39 from which extends radial arms 35 and 37 which are radially slotted to form parallel blades 35a, 35b and 37a and 37b. The secondary bridging contacts 34 and 36 may be flat throughout and are designed and proportioned to have the ends of their blades engage the upper and lower contact surfaces 14a and 14b respectively, of the fixed contact members.

The blades 35a, 35b and 37a, 37b are located directly below and parallel to the blades 25a, 25b and 27a, 27b, respectively.

The primary bridging contact members 22 and 24 lie upon and are secured against the outer surfaces, i. e. the top and bottom surfaces, respectively, of the insulating disc members 26 and 28, respectively. These disc members are alike and the cooperation of the primary bridging members with them is similar. Therefore, reference will be made to only one (26) in describing them in detail. The disc 26 is preferably made from sheet insulation such as fiber glass. Cut into the periphery at points spaced 90° apart are recesses 26a, 26b for the reception of the ends of the blades 25a, 25b and 27a, 27b, respectively, said ends being bent or inwardly offset out of the plane of the central portion 23 so as to be in a position for their inner surfaces to engage the top contact surfaces 13a of the fixed contact members. Preferably, the recesses 26a and 26b are of approximately the size and shape or very slightly larger than the portions of the blades which lie in them.

Of like form and in like manner the ends of the similar blades of the plate member 22 engage the bottom contact surfaces 13b.

Loosely mounted in the center of the movable switch plate assembly, the disc shaped insulating plate 40 has a circular central aperture 42 within which are located the spacing washers 38. In the periphery of the disc 40 are cut notches 44 and 46 at points preferably 90° apart for the reception of the contact heads 13 of the fixed contact members. These notches 44 and 46 are of the same size and contour as said contact head so as to form a close fit with the contact heads when the device is assembled. Preferably the thickness of the plate 40 will be slightly less than the thickness of the inner step 14 of the fixed contact members. Since the plate 40 is located between the bridging contact members 34 and 36 it is necessary for the disc 40 to be of less thickness than the step 14 to enable the blades of the secondary bridging members 34 and 36 to exert pressure upon the surfaces of the steps 14 as the fixed and movable contact parts come into engagement.

To hold the middle disc 40 stationary and to enable it to guide the whole switch blade assembly as the assembly rotates, lugs 48 extend radially from the disc 40 at diametrically opposite points and are held by the switch casing or base 50 or other stationary part of the switch mounting.

From the foregoing the operation of the parts may be understood. Assuming the bridging contacts to be engaged with the fixed contacts. The ends of the blades of the primary bridging members 22 and 24 will press upon the upper and

lower surfaces respectively, of the fixed contact members 10 and 12 while the ends of the blades of the secondary bridging contact members 34 and 36 press upon the upper and lower contact surfaces, respectively, of the steps 14 of the fixed contact members.

Upon turning the switch blade assembly the trailing blades of the secondary bridging members will separate from the step 14 of the fixed contacts slightly before the trailing blades of the primary bridging members separate from the fixed contacts. Contact engagement will, of course, be in the opposite sequence. However, the blades (for example 25a, 27a) of the primary bridging members will separate substantially simultaneously from the fixed contacts surfaces 13a; in like manner the blades (for example 35a, 37a) of the secondary bridging members will separate substantially simultaneously from the fixed contact steps 14. Conversely, contact engagement of the fixed contacts with the two blades of the primary bridging members will, of course, occur simultaneously; and also the engagement of the two blades of the secondary bridging members with the fixed contact steps 14 be simultaneous.

From the foregoing it may now be understood that the provision of four separate arms on the bridging contacts on different levels (two primary and two secondary arms) provides the necessary cross-sectional area to carry currents in the neighborhood of 500 amperes. The provision of the four arms also provides the necessary flexibility for short arms, the arms necessarily being short (as illustrated) because, in certain cases of space limitations.

The slotting of each arm (thereby providing two blades in each) provides a large number of points of contact and better self-alignments when the blades engage the fixed contacts.

The inside or middle stationary insulating disc forms a guide and also an arc barrier to limit the play of the arc incident to switch operation. At the same time the rotating outside insulating discs or barriers act as arc quenching or arc snuffing means.

Modifications within the scope of my invention will occur to those skilled in the art. Therefore I do not limit it to the specific embodiment illustrated in the drawings.

What I claim is:

1. In a rotary switch, fixed contact members each having contact surfaces on two levels and facing in the same direction, a rotary bridging contact assembly comprising a bridging member having arms to slidably engage with the contact surface on one level, a second bridging member having arms, an insulating disc between said bridging members in a plane above both levels of contact surface, means to secure said disc and bridging members together, said disc having recesses in its periphery, the ends of the arms of said second bridging member being offset into said recesses and engageable with the fixed contact surfaces on a second level.

2. In a rotary switch, fixed contact members each having contact surfaces on two levels and facing in the same direction, a rotary bridging contact assembly comprising a bridging member having arms to slidably engage with the contact surface on one level, a second bridging member having arms, an insulating disc between said bridging members, means to secure said disc and bridging members together, said disc having recesses in its periphery, the ends of the arms of

said second bridging member being offset into said recesses and engageable with the fixed contact surfaces on a second level, and an insulating disc which is coaxial with said first disc and is fixedly secured in relation to said fixed contact members and has recesses receiving the portions of said fixed contacts on which are located said first-level contact surfaces.

3. In a rotary switch, fixed contact members each having a pair of contact surfaces on one side thereof and on different levels and a similar pair on the opposite side, also on different levels, a rotary bridging contact assembly comprising a pair of movable insulating discs, a pair of bridging members one overlying the outside surface of one disc and the other overlying the outside surface of the other disc, a second pair of bridging members located between said discs, means securing all of said discs and bridging members together for rotation as a unit, a stationary insulating disc located between said second pair of bridging members and guiding the rotary movement of said movable discs and bridging members.

4. A switch as claimed in claim 3 wherein each bridging member has radially extending arms and is slotted to provide additional points of contact engagement and better alignment with the fixed contact surface that they engage.

5. In a rotary switch, fixed contact members each having a pair of contact surfaces on one side thereof and on different levels and a similar pair on the opposite side also on different levels, a rotary bridging contact assembly comprising a pair of movable insulating discs, a pair of bridging members one overlying the outside surface of one disc and the other overlying the outside surface of the other disc, a second pair of bridging members located between said discs, means securing all of said discs and bridging members together for rotation as a unit, a stationary insulating disc located between said second pair of bridging members and guiding the rotary movement of said movable discs and bridging members, said stationary disc having recesses in its periphery receiving the contact surfaces of said fixed contacts, said stationary and movable discs cooperating with said contact members to quench arcs occurring upon contact separation.

6. A switch as claimed in claim 5 wherein each bridging member has radially extending arms and is slotted to provide additional points of contact engagement and better alignment with the fixed contact surface that they engage.

7. In a rotary switch, fixed contact members each having a pair of contact surfaces on one side thereof and on different levels and a similar pair on the opposite side also on different levels, a rotary bridging contact assembly comprising a pair of movable insulating discs, a pair of bridging members one overlying the outside surface of one disc and the other overlying the outside surface of the other disc, a second pair of bridging members located between said discs, means securing all of said discs and bridging members together for rotation as a unit, a stationary insulating disc located between said second pair of bridging members and guiding the rotary movement of said movable discs and bridging members, said movable discs having recesses in their periphery into which the end portions of the outside bridging members are offset, to permit sliding engagement of said offset ends with one level of said fixed contact sur-

faces, said stationary and movable discs cooperating with said contact members to quench arcs occurring upon contact separation.

8. A switch as claimed in claim 7 wherein each bridging member has radially extending arms and is slotted to provide additional points of contact engagement and better alignment.

9. In a rotary switch, fixed contact members each having a pair of contact surfaces on one side thereof and on different levels and a similar pair on the opposite side also on different levels, a rotary bridging contact assembly comprising a pair of movable insulating discs, a pair of bridging members one overlying the outside surface of one disc and the other overlying the outside surface of the other disc, a second pair of bridging members located between said discs, means securing all of said discs and bridging members together for rotation as a unit, a stationary insulating disc located between said second pair of bridging members and guiding the rotary movement of said movable discs and bridging members, said stationary disc having recesses in its periphery receiving the contact surfaces of said fixed contacts, said movable discs having recesses in their periphery into which the end portions of the outside bridging members are offset, to permit sliding engagement of said offset ends with one level of said fixed contact surfaces, said stationary and movable discs cooperating with said contact members to quench arcs occurring upon contact separation.

10. A switch as claimed in claim 9 wherein each bridging member has radially extending arms and is slotted to provide additional points of contact engagement and better alignment.

11. In a rotary switch, fixed contact members each having a head portion with outer contact surfaces and inner contact surfaces, the inner surfaces of each head portion being closer to the rotational axis of the switch and in different more closely spaced planes than the outer surfaces, a rotary bridging contact assembly comprising a pair of movable insulating discs, a pair of bridging contact plates overlying the outside surfaces of said discs, a second pair of bridging contact plates between said discs and a stationary insulating disc between said second pair of contact plates, means securing together said movable discs and all said bridging contact members for rotation as a unit, said stationary disc acting to guide said rotary unit.

12. A switch as claimed in claim 11 wherein the periphery of the movable discs are recessed and the ends of the outer bridging members are offset into said recesses to slidably engage the outer surfaces of said fixed contacts.

13. A switch as claimed in claim 11 wherein said stationary disc has recesses in its periphery receiving the head portions of the stationary contacts, and said discs cooperate with the contacts to quench arcs incipient upon contact separation.

14. A switch as claimed in claim 11 wherein the periphery of the movable discs are recessed and the ends of the outer bridging members are offset into said recesses to slidably engage the outer surfaces of said fixed contacts, and said stationary disc has recesses in its periphery receiving the head portions of the stationary contacts, and said discs cooperate with the contacts to quench arcs incipient upon contact separation.
